(57) **CLAIM**

The ornamental design for a disc brake calliper body, as shown and described.

DESCRIPTION

FIG. 1 is a perspective view of our new disc brake calliper body;

FIG. 2 is a perspective view of our new disc brake calliper body from the side opposite that of FIG. 1;

FIG. 3 is a side elevational view of our new disc brake calliper body of FIG. 1;

FIG. 4 is a side elevational view of our new disc brake calliper body, from a side opposite that of FIG. 3;

FIG. 5 is an end elevational view of our new disc brake calliper body taken from the right side of FIG. 1;

(Continued)

FIG. 6 is an end elevational view of our new disc brake calliper body from an end opposite that of FIG. 5; FIG. 7 is a top plan view of our new disc brake calliper body; and, FIG. 8 is a bottom plan view of our new disc brake calliper body.
